UNITED STATES PATENT OFFICE

WILLIAM E. DOUGHTY, OF DETROIT, MICHIGAN, ASSIGNOR TO JAMES VERNOR COMPANY, OF DETROIT, MICHIGAN, A CORPORATION OF MICHIGAN

DISPENSING APPARATUS

Application filed June 20, 1930. Serial No. 462,642.

This invention relates to dispensing apparatus and more particularly to improvements in carbonated beverage dispensing apparatus of the character shown and described in my prior Patent No. 1,697,230, dated January 1, 1929.

In dispensing apparatus of this general character it is customary to provide a tank or other source of supply of the beverage under high pressure and to conduct this high pressure beverage to a container or the like constituting a settling chamber where a large proportion of the gas is freed and permitted to escape whereby the resulting low pressure beverage may be dispensed without an objectionable amount of foam.

One of the important objects of the present invention is to provide an improved means for equalizing the pressure in the settling chamber and draft arm whereby the beverage in the draft arm may be maintained, during the inactive periods of the apparatus, at a level substantially equal to the level of the beverage in the settling chamber to thus be below the level of the cooling medium. In this manner the beverage in the draft arm is maintained at the same temperature as the beverage in the settling chamber and properly chilled beverage may therefore be dispensed irrespective of the length of the inactive period of the apparatus.

The particular improvements in this connection forming the subject matter of the present invention consist in the manner in which the settling chamber is connected to the draft arm, this structure providing for the automatic sealing of the gas outlet in the event the level of the beverage in the settling chamber rises beyond a predetermined point due to leakage. Also, this invention contemplates a connection between the gas pressure line and the draft arm which insures the accumulation of pressure in the draft arm above the column of beverage whereby this column of beverage will be forced back to the level of the beverage in the settling chamber irrespective of the length of the draft arm or of the presence of goosenecks or the like therein.

The several objects, advantages and novel

details of construction of an embodiment of this invention will be made more apparent as this description proceeds, especially when considered in connection with the accompanying drawing, wherein the figure is a view partly in elevation and partly in vertical section of a dispensing apparatus constructed in accordance with my invention.

Referring now to the drawing wherein like reference characters indicate like parts, it will be noted that there is illustrated a tank or container 10 adapted to contain a cooling medium such, for instance, as ice and water usually to the level indicated. Arranged within the container 10 is a settling chamber 11 into which the high pressure beverage is introduced from a tank or the like 12, the latter constituting a source of high pressure beverage.

This beverage flows through a pipe or conduit 13 into a cooling coil 14 which in turn is connected to the inlet conduit 15 of a control device indicated generally by the reference character 16.

The details of this control device will not be herein described as it forms no part of this present invention but is fully described and illustrated in my prior patent hereinbefore referred to.

However, by reference to the drawing, it will be noted that the control device comprises essentially a pressure responsive device 17 controlling a valve device 18, which in turn controls the inflow of high pressure beverage from the inlet 15 into the settling chamber.

The control device also includes a float 19, which when the beverage in the settling chamber obtains a predetermined height, acts to close a valve device 20, which in turn controls a gas outlet conduit 21. This gas outlet conduit 21 may be connected to a display chamber (not shown) such as described in my prior patent or may be connected directly to a perforated pipe arranged near the bottom of the container 10 whereby the gas is permitted to escape into the cooling medium for the purpose of agitating the same.

Briefly, the operation of the structure thus far described is as follows: High pressure

beverage will flow in through inlet 15 and assuming that the valve device 18 is open, by reason of the action of spring 22, this high pressure beverage will flow into the interior of the expansible element 17 and then through apertures in the bottom thereof (not shown) and into the settling chamber 11. This will continue until the float 19 has moved upwardly sufficiently to close valve device 20, thereby interrupting the escape of the freed gas through conduit 21. When the escape of gas has been cut off, the pressure of the gas in the settling chamber will rise and, inasmuch as the interior of the expansible member 17 is in communication with the settling chamber, this expansible member will be expanded to close the valve device 18 against the action of spring 22. This cuts off the inflow of the high pressure beverage as will be apparent.

In accordance with the present invention I provide a second conduit 23 connected to the settling chamber 11 as at 24, at a point slightly above the normal desired level of the beverage in the settling chamber. This conduit 23 is connected at its other end as at 25 to the draft arm 26 at a point on the latter adjacent the spigot 27 which, as shown, is controlled by a valve 28. As shown the draft arm 26 may and generally is, of considerable length and may be provided with one or more elbows or goosenecks 29.

The conduit 23 provides a constant source of communication between the settling chamber 11 and the draft arm 26 adjacent the spigot thereof, and under ordinary conditions the accumulated gas in the settling chamber 11 will flow through conduit 23 and into the draft arm 26. Thus after beverage has been dispensed and the valve 28 of spigot 27 has been closed, this gas will fill the draft arm and acting against the valve 28 will accumulate sufficient pressure to force the beverage in the draft arm back downwardly to the level of the beverage in the settling chamber 11. Thus during the inactive periods of the apparatus no beverage remains in that portion of the draft arm outside of the cooling medium so that the first glass full of beverage drawn after the inactive period of the apparatus will be at substantially the same temperature as the remaining beverage in the settling chamber.

Moreover, it sometimes happens that there is a slight leakage in the valve 28 of the spigot 27, which during long periods of inactivity would deplete the pressure in the settling chamber and when the pressure in the settling chamber falls below the pressure at which the spring 22 acts, this spring will open the valve device 18 and permit additional high pressure beverage to flow into the settling chamber until the latter has become filled, thereby rendering the apparatus inoperative for the purpose for which it is

intended. In order to overcome this, I have connected the conduit 23 to the settling chamber as at the point 24 which, it will be noted, is slightly above the desired normal level of the beverage in the settling chamber. Therefore, should there be a constant leakage of the gas through conduit 23 and as a result a rise in the level of the beverage in the chamber 11, this will continue until the level is above the connection 24 whereupon the end of conduit 23 will be sealed against the further escape of pressure through this conduit. Thus the desired pressure can be maintained in the settling chamber and chances of the settling chamber becoming inoperative in the manner above described is eliminated.

Various changes and modifications in the specific construction illustrated may suggest themselves to those skilled in this art and to this end reservation is made to make such changes as may come within the purview of the accompanying claims.

What I claim as my invention is:

1. In apparatus of the class described, a settling chamber, a draft arm connected thereto and a conduit connected to said draft arm and to said settling chamber slightly above the liquid level thereof whereby said conduit will be sealed upon an abnormal rise of the liquid level and before said liquid level reaches the top of said chamber.

2. In apparatus of the class described, a settling chamber, a draft arm connected thereto and a conduit connected to the side wall of said settling chamber intermediate the space normally unoccupied by liquid and to said draft arm adjacent the discharge end of the same.

3. A carbonated beverage dispensing apparatus comprising, a settling chamber for separating a portion of the gas from said beverage, a draft arm communicating with said chamber, and a conduit for conducting a portion of the gas from the settling chamber into the draft arm, the connection between said settling chamber and conduit being intermediate the normal liquid level in said chamber and the top thereof so that an abnormal rise of the beverage in said settling chamber seals said conduit to prevent the passage of gas therethrough.

4. The combination with a settling chamber adapted to receive a carbonated beverage under pressure, and a draft arm connected to said settling chamber, of means including a conduit connecting said settling chamber to said draft arm for conducting a portion of the gas from said settling chamber into said draft arm, said conduit being connected to said settling chamber above the normal beverage level but below the top of said settling chamber whereby an abnormal rise of the beverage level seals the inlet end of said conduit.

5. The combination with a settling cham-

ber adapted to receive a carbonated beverage under pressure, and a draft arm connected to said settling chamber, of means including a conduit connecting said settling chamber to said draft arm for conducting a portion of the gas from said settling chamber into said draft arm, said conduit being connected to the side wall of said settling chamber above the normal beverage level therein and below the top of said settling chamber whereby an abnormal rise of the beverage level seals the inlet end of said conduit, the other end of said conduit being connected to said draft arm adjacent the discharge end thereof, for the purpose set forth.

6. In apparatus of the class described, a settling chamber, a draft arm connected thereto, pressure controlled means for maintaining a predetermined liquid level in said settling chamber, and a conduit connecting the portion of the settling chamber above the normal liquid level to said draft arm, said conduit being sealed by the liquid in said settling chamber upon an abnormal rise of the level thereof.

25 In testimony whereof I affix my signature.
WILLIAM E. DOUGHTY.
